The ornamental design for a handle for a device for applying powder, as shown and described.

DESCRIPTION

FIG. 1 is a perspective view of a handle for a device for applying powder showing my new design;

FIG. 2 is a top plan view thereof; and,

FIG. 3 is a side elevational view.

The broken line showing of the device for applying powder is for illustrative purposes only and forms no part of the claimed design.

The undisclosed bottom surface is planar and unornamented.
